SINK ASSEMBLY

Addison C. Kerby, Detroit, Mich., assignor to
 Briggs Manufacturing Co., Detroit, Mich., a
 corporation of Michigan

Application December 8, 1950, Serial No. 199,802

8 Claims. (Cl. 4—187)

1

This invention relates generally to sink assemblies and more particularly to improved means for mounting and clamping a sink of the flat rim type within an opening in a drainboard, table, counter top, or other supporting structure.

It is customary when mounting a sink of the flat rim type to cut an opening in the counter top, drainboard, or the like to receive the bowl and rim of the sink, the rim being supported within the opening so as to lie substantially flush with the top of the drainboard or counter top. The gap between the edge of the rim and the edge of the opening is closed by a suitable molding which overlaps and is drawn down tightly against the marginal edges of the sink rim and opening to form a seal therebetween.

An object of the invention is to provide improved means for mounting and clamping a flat rim sink within an opening in a drainboard, counter or table top or the like, which means is relatively simple, efficient, inexpensive, and reliable in construction and application, and adapted to accommodate various thicknesses of drainboards or supporting tops, thereby eliminating the necessity of providing different size clamping devices for drainboards or the like of different thicknesses.

A further object of the invention is to provide an improved mounting and clamping device which may be employed anywhere along the molding and which thus ensures a tight engagement between the molding and adjacent edges of the sink rim and drainboard or supporting structure at the corners of the sink as well as along the sides and ends thereof.

More specifically, an object of the invention is to provide a mounting and clamping device embodying a generally T-shaped molding having its top or head adapted to overlie the adjacent edges of the sink rim and supporting structure and its vertical leg extending downward therebetween, the clamp for drawing down the molding comprising two flexibly or hingedly connected clamp elements adapted to swing or rock relative to each other about a horizontal axis extending generally parallel to the sink rim. One of said clamp elements is engageable at an upper end with the underside of the sink rim and is provided with a flange extending toward the vertical leg of the molding and engageable therewith, preferably by means of cooperating hook portions of said flange and leg, so as to pull the latter downward upon downward swinging of the extension in a clamping action. The other of said clamp elements is provided with an exten-

2

sion engageable with the underside of the adjacent edge of the drainboard or supporting structure, so as to swing upward against the same in the clamping action. The clamping action is preferably effected by screw means engaging portions of both elements so as to swing the same in the aforesaid clamping actions when tightened.

In a preferred construction, the clamp element engaging the underside of the sink rim and having the aforesaid extension engaging the depending leg of the molding extends generally vertically. The other clamp element extends generally horizontally and is detachably fulcrumed intermediate its ends on the lower end of the vertical element and supported thereby, one end of the horizontal element being on one side of the fulcrum axis and underlying the adjacent edge of the drainboard or supporting structure and the other end being on the other side of the fulcrum axis and engaged by an adjustable screw which extends generally vertically and also engages at its upper end still another extension of the vertical element. The two extensions engaged by the screw are swung away from each other when the screw is turned in a clamping action. Accordingly the extensions of the clamp elements on the other side of the fulcrum are swung toward each other in the clamping action, drawing the molding tightly downward relative to the drainboard or supporting structure. It is apparent from the foregoing that the adjustable screw does not come in contact with either the sink rim, molding, or drainboard or supporting structure, but engages a flange or extension of the vertical clamp element. The clamp may thus be readily applied at any position along the molding, including the portions thereof adjacent the corners of the sink.

Also in a preferred construction, the detachable pivotal connection between the two clamp elements is completed by means of a slot in the horizontal element intermediate its ends. The lower end of the vertical element is removably insertable through the slot and is provided with a tab or projection extending angularly from said lower end and adapted to support the horizontal element thereon. The slot is preferably slightly oversize with respect to the portion of the vertical element passing therethrough, so as to facilitate passage of the angularly extending tab and also to permit a limited pivotal movement of the two clamp elements relative to each other about an axis generally parallel to the sink rim as aforesaid.

Still another object is to provide an improved mounting and two element clamp of the foregoing character wherein the extension of the horizontal clamp element adapted to underlie the supporting structure is offset vertically from the portion of the horizontal clamp element at the slot or fulcrum. Accordingly, the horizontal element may be selectively installed in either of two positions inverted or upside down with respect to each other. In one position, with the drainboard engaging extensions of the horizontal element offset upward, the clamp is adapted for drainboards or supporting structures of minimum thickness. In the reversed position, with the outer drainboard engaging extension offset downward, the clamp is adjusted for drainboards or supporting structures of maximum thickness.

Other objects of this invention will appear in the following description and appended claims, reference being had to the accompanying drawings forming a part of this specification wherein reference characters designate corresponding parts in the several views.

Fig. 1 is a fragmentary plan view showing a portion of a flat rim sink installed in a supporting structure by means of mounting and clamping devices embodying the present invention.

Fig. 2 is a fragmentary vertical section taken substantially through lines 2-2 of Fig. 1 looking in the direction of the arrows.

Fig. 3 is an exploded perspective view illustrating the component parts of the mounting and clamping device.

Fig. 4 is a view similar to Fig. 2, but showing the clamping device adjusted for use with a slightly thicker supporting structure.

Fig. 5 is a view similar to Fig. 4, but showing the horizontal clamp element in an inverted position adjusted for use with a thicker supporting structure.

Fig. 6 is a view similar to Fig. 5, but showing the clamping device adjusted for use with a slightly thicker supporting structure.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there is illustrated a flat rim sink 10 installed within an opening in a drainboard, counter or table top or other supporting structure designated generally by the numeral 11. The sink 10 may be of any conventional type having the usual basin or bowl 12 terminating around the upper edge thereof in a continuous outwardly extending horizontal flange or rim 13. The drainboard or supporting top 11 may comprise any customary supporting structure as, for example, a laminated material such as plywood suitably covered with a water resistant layer or sheeting, such as linoleum.

For the purpose of installing the sink 10 a generally rectangularly shaped opening 14 is cut in the drainboard or supporting top 11, this opening being somewhat larger than the area of the sink so as to permit the sink to be inserted freely into the opening with suitable clearance between the marginal edges of the rim 13 and opening 14 to accommodate a molding 15 by means of which

the sink is supported within the opening in the drainboard or supporting structure.

The molding 15, which is usually plated to present a finished border around the marginal edges of the sink, comprises a generally rectangular frame which is generally T-shaped in construction. Thus, the molding frame, which may be made of sheet metal, is provided with a top or head 16 which is preferably crowned and of suitable width so as to overlie the adjacent edges of the sink rim 13 and drainboard 11. The molding 15 is also formed with a vertical leg 17 terminating at its lower edge in an inclined flange 18 forming a hook portion. Thus, when the molding is installed, as illustrated in Fig. 2, the vertical leg 17 projects downwardly between the edge of the sink rim and the edge of the opening 14 in the drainboard or supporting structure 11, and the crowned head or top 16 of the molding overlies the upper surfaces of these edges.

The clamping means in the present instance comprises separable upper and lower elements indicated generally by the numerals 19 and 20 respectively, Fig. 3. In operation the upper element 19 extends generally vertically and terminates in upper later edge portions 19a adapted to engage the underside of the sink rim 13, Fig. 2. At its lower end, the element 19 extends downward in a neck portion 19b of reduced width which terminates in a tab or seat 21 extending outward toward the adjacent edge of the drainboard or supporting structure 11 at a slight decline substantially in parallelism with the hook 18. Each of the opposed vertical sides of the body 19 terminates in an outward extending lateral flange 22 which provides an overhanging outward declined edge or hook portion 22a located approximately midway between the seat 21 and uppermost edge 19a. As indicated in Fig. 2, the paired lateral hooks 22a are adapted to overlie and engage the molding hook 18. Above the hook portion 22a, the upper edge 22b of each side flange 22 curves upward and inward to form in effect cam edges converging with the corresponding uppermost lateral edge 19a. Intermediate the lateral edges 19a, the upper portion of the element 19 is folded inward to provide a generally horizontal screw engaging tab 23.

The lower clamp element 20 extends generally horizontally in operation and comprises an outer screw engaging platform 20a provided with a centrally located slot 24 adapted for passage of the tab 21 and reduced neck portion 19b, whereby the two elements 19, 20 are assembled with the latter element supported on the seat 21, Fig. 2. The slot 24 is slightly oversize with respect to the thickness of the portions 19b and 21, so as to permit their passage readily and to permit freedom of limited pivotal or swinging movement of the assembled elements 19 and 20 with respect to each other about a horizontal axis extending generally parallel to the edges of the sink rim 13 and drainboard 11. The element 20 is also provided with an outer platform 20b offset vertically from the platform 20a, the outer platform 20b being adapted to underlie and engage the adjacent edge of the drainboard 11 and the inner portion 20a being adapted to underlie the screw engaging tab 23 in vertically spaced relation. Inward of the slot 24, the platform 20a is provided with a vertical bore 25. A clinch nut 26 for a machine screw 27 is suitably anchored on the portion 20a with its threaded bore aligned with the bore 25.

In application of the foregoing structure, the

sink 10 is assembled within the opening 14 in the drainboard or supporting structure 11 with the molding 15 installed as illustrated in Fig. 2. Any suitable number of clamping devices 19, 20 are employed around the sides and ends of the sink so as to cooperate with the molding 15 and to provide adequate support for the sink. Each pair of clamp elements 19 and 20 are assembled as aforesaid, Fig. 2, with the neck 19b passing through the opening 24 and the tab or seat 21 underlying the adjacent portion of the platform 20a. The outer platform 20b is disposed under the edge of the drainboard 11, with the upper edge 19a disposed below the sink rim 13, and the paired lateral hooks 22a are hooked over the molding flange 18. Engagement between the hook portions 18 and 22a is facilitated by reason of the outward decline of the seat 21 and the dimensions of the slot 24. Thus the upper or vertical clamp element 19 may be pivoted clockwise in Fig. 2 about its lower end relative to the lower element 20, so as to elevate the hook 22a and permit the same to slide over the upper edge of the inclined hook 18 and toward the molding leg 17.

The screw 27 is then screwed upward through the nut 26, causing the upper end of the screw 27 to engage the underside of the tab 23 and pivot the clamp element 19 counterclockwise in Fig. 2 to the vertical position shown. In this action the hook 22a is pivoted outward and downward tightly into engagement with the hook flange 18, the molding 15 is drawn downward and its head 16 pressed tightly against the adjacent upper surfaces of the drainboard 11 and sink rim 13, and the upper portions of the element 19 are rocked or swung outward or counterclockwise on the curved cam edges 22b so as to force the edges 19a outward and upward snugly against the sink rim 13 directly above the slot 24. In the same action the inner platform 20a of the lower or horizontal clamp element 20 is forced downward, causing the outer platform 20b to swing upward tightly against the underside of the supporting structure 11. As a result, the sink rim 13 is supported on the upper clamp edge 19a and clamped tightly between the latter and overlying portion of the molding head 16. Similarly the edge of the drainboard 11 adjacent the opening 14 is clamped tightly between the overlying portion of the molding head 16 and horizontal clamp portion 20b. With the usual sealing compound interposed between the molding head 16 and underlying edge portions of the sink rim 13 and drainboard 11, the operation of tightening the several clamps 19, 20 in the manner illustrated will produce a tight permanent seal.

If the thickness of the drainboard 11 is somewhat greater or less than the vertical distance between the molding head 16 and clamp platform 20b in the horizontal position of the latter, the horizontal element 20 may be tilted slightly counterclockwise or clockwise correspondingly about its pivotal connection with the neck 19b, so as to tightly engage the offsize drainboard. Thus, as illustrated in Fig. 4, where the drainboard 11a shown is somewhat thicker than the drainboard 11, the horizontal platform 20b is tilted downward or counterclockwise from the horizontal to receive the drainboard 11a between the clamp portion 20b and molding head 16. In other respects, the sink mounting and clamping action is effected as discussed above.

For drainboards of greater thickness, the clamp elements 19 and 20 are assembled as dis-

cussed above, but with the lower horizontal element 20 inverted or upside down from its position shown in Figs. 2 and 3. Minor adjustments of the clamp to conform to varying drainboard thicknesses is accomplished as before by tilting the clamp element 20 from the horizontal. Thus for the drainboard 11b of Fig. 5, the clamp elements 19 and 20 are assembled with the offset platform 20b below the platform 20a and tilted slightly upward. In Fig. 6, a drainboard 11c of even greater thickness is accommodated by assembling the clamp elements 19 and 20 as in Fig. 5, but with the offset platform 20b tilted downward.

15 I claim:

1. In a means for mounting a flat rim sink in an opening in a supporting structure, a molding having upper portions adapted to overlie adjacent edges of the sink rim and supporting structure and having a depending portion adapted to extend between said edges, a pair of clamp elements having an articulate connection therebetween to provide for relative movement thereof, one clamp element having a portion engageable with said depending portion to press downward thereon in a clamping action and having a portion engageable with the underside of the sink rim, the other clamp element having a portion engageable with the supporting structure to press upward thereon in said clamping action, and adjustable means engageable with said two clamp elements for imparting relative movement thereto.

2. In a means for mounting a flat rim sink in an opening in a supporting structure, a molding having upper portions adapted to overlie adjacent edges of the sink rim and supporting structure and having a depending portion adapted to extend between said edges, an upper clamp element engageable with the underside of the sink rim and having a clamping portion engageable with said depending portion, a lower clamp element having an articulate connection with the upper clamp element and having a clamping portion engageable with the underside of the supporting structure, and adjustable means engageable with said two clamp elements to impart relative movement thereto.

3. In a means for mounting a flat rim sink in an opening in a supporting structure, a molding having upper portions adapted to overlie adjacent edges of the sink rim and supporting structure, an upper clamp element engageable with the underside of the sink rim and having a clamping portion adapted to be hooked over a portion of said molding, a lower clamp element having an articulate connection with the upper clamp element and having a portion engageable with the underside of the supporting structure, and adjustable screw means engageable with the lower clamp element and having its upper end engageable with the upper clamp element to impart relative movement to said clamp elements.

4. In a means for mounting a flat rim sink in an opening in a supporting structure, a molding having upper portions adapted to overlie adjacent edges of the sink rim and supporting structure and having a depending portion adapted to extend between said edges, an upper clamp element engageable with the underside of the sink rim and having a clamping portion adapted to engage said depending molding portion, a lower clamp element having an articulate connection with the upper clamp element to provide for connection with the latter in either of

two positions inverted with respect to each other and having a vertically offset portion engageable with the supporting structure, and adjustable means engageable with said two clamp elements to impart relative movement thereto.

5. In a means for mounting a flat rim sink in an opening in a supporting structure, a molding having upper portions adapted to overlie adjacent edges of the sink rim and supporting structure and having a depending portion adapted to extend between said edges, an upper clamp element engageable with the underside of the sink rim and connected to said depending molding portion and also having an extension directed generally away from said depending molding portion, a lower clamp element having an articulate connection with said upper clamp element for movement relative thereto, said lower clamp element having a portion adapted to extend below the supporting structure for engagement therewith and also having a generally oppositely directed extension spaced vertically from said extension of the upper clamp element, and adjustable means engaging said vertically spaced extensions to impart relative movement thereto.

6. In a means for mounting a flat rim sink in an opening in a supporting structure, a molding having upper portions adapted to overlie adjacent edges of the sink rim and supporting structure and having a depending portion adapted to extend between said edges, an upper clamp element engageable with the underside of the sink rim and connected to said depending molding portion and also having an extension directed generally away from said depending molding portion, a lower clamp element having an articulate connection with said upper clamp element for movement relatively thereto and having two extensions directed generally in opposite directions from the connection between said two elements, one of the last named extensions comprising a portion adapted to extend below the supporting structure for engagement therewith and the other extension being vertically spaced below the extension of the upper clamp element, and adjustable means engaging said vertically spaced extensions to move the same away from each other.

7. In a means for mounting a flat rim sink

in an opening in a supporting structure, a molding having upper portions adapted to overlie adjacent edges of the sink rim and supporting structure and having a depending portion adapted to extend between said edges, an upper clamp element engageable with the underside of the sink rim and connected to said depending molding portion, a lower clamp element, means for connecting the lower element in either of two positions to the upper element for movement relatively thereto, the lower element in one of said positions being inverted with respect to itself in the other position, the lower clamp element having a portion adapted to underlie the supporting structure for engagement therewith in either position and the locations of the clamping portion in said two positions being vertically offset from each other, and adjustable threaded means engaging said lower clamp element and having its upper end engaging a part of the upper clamp element.

8. In a structure for mounting a flat rim sink in an opening in a supporting structure, a molding having upper portions adapted to overlie adjacent edges of the sink rim and supporting structure and having a depending portion adapted to extend between said edges, the depending portion having a hook-like flange, an upper clamp element engageable with the underside of the sink rim and having a portion adapted to hook over said flange, a lower clamp element having an articulate connection with the upper element and having a portion adapted to extend below and in engagement with the supporting structure, and adjustable means engaging said two clamp elements for effecting relative movement thereof.
